(57) **CLAIM**

The ornamental design for a pedicure sink, as shown and described.

DESCRIPTION

FIG. 1 is a front perspective view of a pedicure sink showing my new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a back view thereof.

The ornamental design which is claimed is shown in solid lines in the drawings.

The broken lines in the drawings are for illustrative purposes only and form no part of the claimed design.
